UNITED STATES PATENT OFFICE.

ARTHUR W. REED, OF ORVISBURG, MISSISSIPPI.

AUTOMATIC CAR-BRAKE.

SPECIFICATION forming part of Letters Patent No. 698,319, dated April 22, 1902.

Application filed July 11, 1901. Serial No. 67,899. (No model.)

To all whom it may concern:

Be it known that I, ARTHUR W. REED, a citizen of the United States, residing at Orvisburg, in the county of Pearl River and State 5 of Mississippi, have invented a new and useful Automatic Car-Brake, of which the following is a specification.

The invention relates to improvements in automatic car-brakes.

10 The object of the present invention is to improve the construction of automatic car-brakes and to provide a simple, inexpensive, and efficient device designed for use on various kinds of cars, especially logging-cars, 15 and adapted to be readily applied to the same and capable of enabling the brakes to be controlled and applied by the engineer.

15 The invention consists in the construction and novel combination and arrangement of 20 parts hereinafter fully described, illustrated in the accompanying drawings, and pointed out in the claims hereto appended.

In the drawings, Figure 1 is a plan view of 25 a portion of a car provided with a device constructed in accordance with this invention. Fig. 2 is a similar view, the transverse lever being disconnected from the coupling-pole and the chain being attached to the same to arrange the parts for backing. Fig. 3 is a longitudinal sectional view. Fig. 4 is a transverse sectional view.

Like numerals of reference designate corresponding parts in all the figures of the drawings.

30 1 designates a portion of the frame of a logging-car having longitudinal draft-timbers 2, connected by upper and lower transverse bars 3 and 4 and receiving the shank 5 of a draw-head 6, which is designed to be connected by a coupling-pin 7 with a coupling-pole 8 of the ordinary construction. The shank of the draw-head is connected by a rod or bolt 8' with a heavy coiled spring 9 and front and rear transverse plates 10 and 11, slidably connected with the draft-timbers and located at the ends of the coiled cushioning-spring and adapted to compress the same when the car-coupling is drawn outward or forced inward with sufficient force. The car-coupling, which 45 consists of the said draw-bar and draw-head, is capable of a limited longitudinal movement, and this movement permits an automatic op-

eration of the car-brakes by the construction hereinafter described. The car-coupling may be mounted in any other suitable manner to 55 secure the necessary longitudinal movement.

Fulcrumed on one side of the frame of the car is a transversely-disposed lever 11', which is connected at its outer end with a longitudinal rod 12, designed to extend to and be 60 connected with the ordinary car-brake, (not shown,) whereby when the rod is moved outward longitudinally an application of the brakes will be effected. The outer end of the rod is connected with the outer arm of the 65 transverse lever 11' by a short chain 13, and the lever is provided with a series of perforations 14, adapted to receive a bolt or other suitable fastening device for connecting the short chain to the lever and capable of enabling the leverage to be changed. The lever 70 11 is provided with a central aperture for the reception of a pivot 15, and its inner arm is provided at its outer portion with a fork or bifurcation 16 for the reception of a longitudinal bar 17. The longitudinal bar 17 extends forward from the transverse lever and is pivoted detachably by a pin 18 to a bracket or bar 19 of the coupling-pole 8. The rear portion of the longitudinal bar 17 is provided 80 with a series of perforations 20 to receive the pivot 21 for connecting the said bar 17 to the inner end of the transverse lever. The bracket or bar, which is suitably secured to the coupling-pole, has its rear portion offset from the 85 same, and the front end of the bar 17 is bifurcated or forked to receive the said bracket or bar 19. The cushioning-spring of the car is designed to be of sufficient strength to permit the car to be backed on a level or slight 90 incline without compressing the spring or applying the brake; but when the cars are in motion the engineer, by reducing the speed of the locomotive, may create sufficient pressure to compress the spring and produce an 95 application of the brakes. In this manner the brakes will be automatically applied, and a train will be completely under the control of the engineer.

When it is desired to arrange the parts for 100 backing a train of cars, the transverse lever is disconnected from the coupling-pole by detaching the front end of the bar 17, and the rod 12 is connected with the coupling-pole by

a chain 21'. The chain 21', which is connected at its rear end to the outer arm of the lever 11' and which may form a continuation of the chain 13, is provided at its front end with a hook 22, adapted to engage an eye 23 of the coupling-pole, as clearly illustrated in Fig. 2 of the accompanying drawings. The eye 23 is preferably formed by an eyebolt, which passes through the coupling-pole. 5

10 Should the engine while backing a train in this manner reduce its speed, the chain will be drawn taut and the rod drawn outward and the brakes applied. When the inner end of the transverse lever 11' is connected 15 with the coupling-pole, as illustrated in Fig. 1 of the drawings, the chain 21' is disconnected from the coupling-pole and hangs down from the outer arm of the lever 11', as illustrated in Fig. 4.

20 It will be seen that the attachment is exceedingly simple and inexpensive in construction, that it is adapted to be readily applied to a car, and that it is capable of enabling the brakes to be controlled by the engineer. It 25 will also be apparent that the attachment is applicable to various kinds of cars and that the attachment may be readily arranged either for backing or hauling a train.

30 The device is adapted for use on cars not employing coupling-poles, and the bracket or bar 19 or analogous member will be mounted on a car, motor, or other vehicle for the reception of the detachable connecting-bar 17, and the chain 21' will then be connected to 35 such car.

What is claimed is—

1. In a device of the class described, the combination with a car having a car-coupling capable of longitudinal movement, of a trans- 40 verse lever fulcrumed on the car and designed

to be connected at one end with the brake-operating connections, and means for connecting either the inner or outer arm of the lever with the draft mechanism, whereby the parts are arranged either for backing or hauling a car or train, substantially as described. 45

2. In a device of the class described, the combination with a car provided with a car-coupling capable of longitudinal movement, of a transverse lever fulcrumed between its ends on the car, means for connecting the outer end of the lever with a car-brake, a coupling-pole connected to the car-coupling, the longitudinal bar connected to the inner arm of the transverse lever and detachably secured to the coupling-pole, and a chain connected with the outer arm of the lever and provided with means for detachably engaging the coupling-pole, substantially as described. 55

3. In a device of the class described, the combination with a car having a car-coupling capable of longitudinal movement, of a brake-rod, a flexible connection extending from the outer end of the brake-rod, a transverse lever fulcrumed between its ends and secured to the said flexible connection, a coupling-pole connected to the car-coupling and provided with a bracket or bar, a bar pivoted to the inner end of the lever and detachably secured to the bracket or bar of the coupling-pole, 70 and means for detachably connecting the outer end of the lever with the coupling-pole, substantially as described.

In testimony that I claim the foregoing as my own I have hereto affixed my signature in 75 the presence of two witnesses.

ARTHUR W. REED.
